(57) **CLAIM**

The ornamental design for an eyeglasses holder, as shown and described.

DESCRIPTION

FIG. 1 is a perspective view showing my new design; FIG. 2 is a front view showing the eyeglasses holder in a condition of use with a wearer and a pair of eyeglasses; FIG. 3 is a front view of FIG. 1; FIG. 4 is a back view thereof; FIG. 5 is a left side view thereof; FIG. 6 is a right side view thereof; FIG. 7 is a top view thereof; FIG. 8 is a bottom view thereof; FIG. 9 is a perspective view showing another embodiment of my new design for an eyeglasses holder; FIG. 10 is a front view showing the eyeglasses holder in a condition of use with a wearer and a pair of eyeglasses; FIG. 11 is a front view of FIG. 9; FIG. 12 is a back view thereof; FIG. 13 is a left side view thereof; FIG. 14 is a right side view thereof; FIG. 15 is a top view thereof; and, FIG. 16 is a bottom view thereof.

The consistent-length broken lines on the claimed surfaces depict stitching that forms no part of the claimed design. The alternating-length broken lines in the drawings depict environmental structure in the form of garments, a person, and a pair of glasses that also form no part of the claimed design. FIGS. 1 through 8 illustrate a left-handed eyeglasses holder, it is to be understood that the invention includes a right-handed eyeglasses holder which is illustrated as a mirror image of any or all of the views shown in FIGS. 1 through 8 in FIGS. 9 through 16.
